UNITED STATES PATENT OFFICE.

BENJAMIN MARK WARD, OF MATTOON, ILLINOIS.

DESIGN FOR A MATCH-SAFE.

SPECIFICATION forming part of Design No. 36,478, dated August 4, 1903.

Application filed July 3, 1903. Serial No. 164,247. Term of patent 14 years.

To all whom it may concern:

Be it known that I, BENJAMIN MARK WARD, a citizen of the Kingdom of Great Britain, and a resident of Mattoon, in the county of Coles 5 and State of Illinois, have invented a new, original, and ornamental Design for a Match-Safe.

Reference is to be had to the accompanying drawing, forming a part of this specification, 10 in which the figure is a perspective view of a match-safe, showing the design.

I claim as new and desire to secure by Letters Patent—

The ornamental design for a match-safe, herein shown.

In testimony whereof I have signed my name to this specification in the presence of two subscribing witnesses.

BENJAMIN MARK WARD.
